(57) **CLAIM**

I claim the ornamental design for the container having sliding door, as shown and described.

DESCRIPTION

FIG. 1 is a perspective view of container having a sliding door in a closed position, the container and the sliding door including dashed lines in the length, width, and depth dimensions to indicate that the length, width, and depth dimension may vary from that shown and form no part of the claimed design, the sliding door including dashed lines to show that different surface features on the sliding door are possible and form no part of the claimed design;

FIG. 2 is a perspective view of the container of FIG. 1 with the sliding door in the open position to reveal a dispensing opening, the dispensing opening shown in dashed lines;

FIG. 3 is a top view of the container of FIG. 1, the sliding door in the open position to reveal the dispensing opening; FIG. 4 is a top view of the container of FIG. 1, the sliding door in the closed position to conceal the dispensing opening;

FIG. 5 is a bottom view of the container of FIG. 1;

FIG. 6 is a side view of the container of FIG. 1;

FIG. 7 is a side view of the container of FIG. 1 showing the side opposite that shown in FIG. 6;

FIG. 8 is a front view of the container of FIG. 1; and,

FIG. 9 is a back view of the container of FIG. 1.
